UNITED STATES PATENT OFFICE.

EMANUEL J. LEWIS AND JAMES G. McGREEVY, OF CHICAGO, ILLINOIS.

DUPLEX ENVELOPE.

Application filed February 3, 1921. Serial No. 442,221.

To all whom it may concern:

Be it known that we, EMANUEL J. LEWIS and JAMES G. McGREEVY, citizens of the United States, and residents of Chicago, in the county of Cook and State of Illinois, have invented certain new and useful Improvements in Duplex Envelopes, of which the following is a specification.

This invention relates to improvements in duplex envelopes, and more particularly to envelopes constructed to provide in a single container, matter which has been designated by the Post Office Department to be of different classes, and therefore subject to different rates of postage. An envelope of this character is used to transmit mailable matter of different classification in a single envelope; as, for instance, where a written letter, which is first class matter, accompanies a circular, catalog, or other printed matter coming within a different classification.

The object of the present invention is not only to provide an envelope adaptable for mailing purposes in the manner already suggested, but to provide means for making such envelopes which will be efficient from a standpoint of manufacture, and therefore capable of being produced at a low cost of manufacture, and further, to provide an envelope in such a form as to comply strictly with the regulations of the Post Office Department pertaining to addressing and stamping of matter transmitted thru the mails in the so-called duplex envelopes. These regulations provide that the first class matter shall be enclosed within a separate compartment from the printed or second class matter compartment; that each compartment shall bear a postage stamp at the upper right hand corner of each compartment; that each compartment shall bear a return address at the upper left hand corner, and that the addressee's name and address shall appear at least on the face of the first class compartment at the customary location.

The type of envelope embodying the invention is illustrated in the accompanying drawings, there having been selected two forms which the envelope may assume, altho both involving the same distinctive features of construction. In the drawings,

Fig. 1 is a view in elevation of the blank cut from a single sheet of paper, showing the location of the adhesive and the scored

fold lines along which the different elements are folded to form a complete envelope,

Fig. 2 is a view in front elevation of the 60 folded envelope,

Fig. 3 is a view in rear elevation of the blank partially folded, and a portion of the rear panel broken away to show the interior construction, 65

Fig. 4 is a view in transverse section of the envelope taken on line 4—4 of Figure 3,

Fig. 5 is a view in elevation corresponding to Figure 1, but disclosing a modified 70 form of the envelope,

Fig. 6 is a view in front elevation of the folded envelope formed from the blank shown in Figure 5,

Fig. 7 is a view in rear elevation of the 75 modified form of envelope, and

Fig. 8 is a view in longitudinal section taken on line 8—8 of Figure 6.

Describing the general features of the envelope embodying the invention, which are 80 common to both forms herein disclosed, the same, in its initial form, consists of a blank which is cut from a single sheet of paper of the quality and weight ordinarily used in the manufacture of envelopes. The blank, as it appears prior to folding, comprises several panels and flaps, which are separated from one another by means of score or fold lines along which the parts are folded in the operation of forming and 90 sealing the finished envelope.

Referring first to the form of envelope disclosed in Figures 1 to 4 inclusive, the blank, as appearing in Figure 1, comprises a front panel 1, a rear panel 2, and an inside panel 3, these panels, when folded upon each other in the manner hereinafter to be described, forming the body of the envelope. The front and rear panels 1 and 2, which obviously form the front and back of the envelope, are rectangular in shape and are of the same size, being separated by a longitudinal fold line 4 extending lengthwise of the panels. On the opposite side of the rear panel 2, and occupying the same relative position thereto as the front panel 1, is the inside panel 3, so called because it ultimately comprises a position inside of the envelope, this panel being separated from the rear panel 2 by means of a fold line 5 extending lengthwise between the panels, and parallel to the fold line 4. The inside panel 3

is of the same length as the front and rear panels 1 and 2, but in width is considerably less than the said front and rear panels 1 and 2, such width being preferably expressed as from one-half to two-thirds the width of the other panels.

Surrounding the free edges of the front panel 1 are a number of flaps which may be located and identified as follows: Extending 10 along the upper transverse edge of the front panel 1 is a relatively large flap 6, separated from the panel 1 by the fold line 7. This flap 6, as will hereinafter be seen, closes the larger compartment of the envelope, and 15 inasmuch as such larger compartment is to contain the printed matter, the flap is not gummed, but is provided with a suitable fastening means permitting ready access to the contents, in accordance with the regulations of the Post Office Department. The 20 fastening means disclosed consist of a hole 8 punched in the flap, and a metal clip 9 inserted in the back panel at a point to engage the hole 8 when the flap 6 is folded into closed position. However, the fastening device may be applied at any convenient point in the process of manufacture, and not necessarily prior to the folding of the blank, as would appear from an examination 25 of Figure 1. Immediately opposite the large flap 6, and extending the full width of the front panel 1, is a relatively narrow flap 10 separated from the front panel by means of the fold line 11. This flap, as will hereinafter appear, forms a permanent closure for the lower end of the larger compartment of the envelope, and for this reason is provided with a gummed surface 30 as at 12. Along the free longitudinal edge 40 of the front panel are formed two flaps 13 and 14, the flap 13 being the longer and wider of the two, extending, as it does, substantially throughout two-thirds of the length of the front panel from the lower edge 45 thereof, as indicated by the fold line 11 toward the upper edge indicated by the fold line 7. The shorter and narrower flap 14 extends from the upper end of the flap 13, to the upper edge of the front panel 1, 50 terminating at the upper edge thereof as indicated by the fold line 7. As will hereinafter appear, the larger flap 13 is the sealing flap of the first class matter compartment, and therefore is provided with a 55 gummed inner surface as at 15. The flap 14, as will also be brought out, forms a permanent sealing flap, and therefore is gummed on its inner surface, as at 16. These 60 flaps are separated from the front panel by means of a longitudinal fold line 17 on the opposite side of the front panel 1 from the fold line 4, and parallel therewith. There are also strips of gum or adhesive 65 applied to the inside surface of the front panel, altho the location of the same will

be better understood in connection with the description of the manner in which the blank is folded to form the finished envelope.

Assuming that the blank is cut, scored and gummed in the manner just described, the operation of folding and sealing of the several flaps will be understood from the following: The first step in the folding process is to fold the inside panel 3 along 70 the fold line 5, and over upon the rear panel 2. This operation having been completed, the rear panel 2 with the inside panel in folded position, is folded over and upon the front panel 1, so that the parts 75 occupy the positions as shown in full lines in Figure 3; namely, with the inside panel in flatwise contact with the inner surface of the front panel, and extending lengthwise thereof throughout the outer portion 80 thereof. Referring to Figures 1 and 2, the application of the adhesive to the inside surface of the front panel may now be located with reference to the folded position of the inside panel 3. Extending longitudinally of the front panel, and substantially midway between the fold lines 4 and 17, is a strip of gumming 18 extending the full length of said panel, and positioned so as to have sealing contact with the free edge 85 of the panel 3 in its final folded position. In addition to the strip of adhesive 18 there are provided shorter strips of adhesive 19 located between the upper end portion of the strip 18 and the flap 14, the length of 90 said strips 19 being substantially the same as said flap 14. It is therefore manifest that when the inside panel 3 is folded against the strips of adhesive 19, and the corresponding portion of the strip 18, that 95 the same will be sealed to the front panel 1 along the free edge of the panel 3, and throughout the area intermediate the upper end portion of the adhesive strip 18 and the flap 14. It is to be understood, of course, 100 that the application of the adhesive is made prior to the folding operation so that the sealing takes place simultaneously with the folding operation.

The next operation is to fold the flaps 12 115 and 14 over and downwardly against the rear panel 2 in position shown in dotted lines in Figure 3. In this manner the lower end of the envelope is permanently closed by means of the flap 12, and a sealing contact effected between the superimposed edges of the front and rear panels throughout the length thereof co-extensive with the flap 14, and adjacent the sealed area produced by the strips of gumming 19. It is to be observed that the envelope forms a large compartment having an area equal to that of the front or rear panels 1 and 2, this compartment being open at its upper edge, and adapted to be closed by means of the flap 120 125 130 135

6. Furthermore, a somewhat smaller compartment is formed between the inside panel 3 and the front panel 1, this compartment being considerably smaller in size and confined between the strip of adhesive 18, the inner end of the strips of adhesive 19-19, and the corresponding portions of the fold lines 17 and 11. The opening of this smaller compartment extends along the fold line 17, and is closed by the flap 13, this flap being sealed after the letter is inserted in the smaller compartment.

The appearance of the envelope after it has been finished, its contents inserted therein, and proper postage applied, is disclosed in Figure 2. For the purpose of defining the limits of the different compartments, and for indicating their relative positions, the lines 20 and 21 are preferably printed on the front face of the envelope, the presence of these lines also determining the location of the return addresses 22, which properly appear in the upper left hand corner of each compartment. Similarly, the outline of the smaller or letter compartment determines the position of the stamps 23, which according to postal regulations must be affixed at the upper right hand corner of each compartment.

If desired, an envelope of this character may utilize the so-called "window" or transparent panel feature, which eliminates the necessity of addressing the outside of the envelope by utilizing the address appearing on the inserted letter. This transparent panel, as indicated at 24, may be properly located and inserted in the blank during the process of manufacture. In an envelope constructed in this manner, the use of the open panel address space is especially adaptable by reason of the location of the opening thru which the correspondence is inserted; that is to say, the open panel occupies the same position in a duplex envelope that it does in a single envelope, with the exception that the letter would be inserted from the lower edge rather than from the upper edge. This difference, however, may be readily provided for by the proper location of the transparent panel 24 with reference to the address as written or typed upon the folded letter inserted within the letter compartment.

In Figures 5, 6, 7, and 8 is illustrated a modified form of the envelope identical to the form already described in detail; in fact, it provides an envelope of the same shape, altho involving a different arrangement of the flaps and openings to the compartments. In the form previously described, the contents of the large compartment are inserted from the narrower side of the envelope, and the letter inserted into the smaller compartment from the longer side of the envelope, whereas in the modified

form of envelope, the opening of the large compartment is located at the edge of the longer side of the envelope, and the entrance to the letter compartment is along the shorter side of the envelope. In order to avoid a detailed description of the modified form of envelope, the reference numerals are repeated to indicate the corresponding parts in the modified construction, attention being directed to the following departures in arrangement and disposition of the several panels and flaps. The front, rear and inside panels bear the same relation to each other, except that the fold lines 4 and 5 coincide with the shorter edges of the panels rather than the longer edges. Similarly the flaps 6 and 12 are located on opposite sides of the front panel, but are located at the longer edges rather than the shorter edges. The flaps 13 and 14 bear the same relation to the flaps 6 and 12, and to the several panels, as before, but are located at the shorter free edge of the front panel instead of along the longer free edge, as in the previously described form of envelope. So, also, a similar disposition of the gummed strips 18 and 19 is employed, altho they are arranged parallel to the shorter sides of the front panel, and disposed at a greater distance apart, but with the same function in view; namely, of sealing the inside panel against the front panel to form the letter compartment, which, it will be noted, extends lengthwise of the front panel in the same manner as it did before. However, it is to be observed that the entrance to the letter compartment is now at one end thereof rather than along the longitudinal edge so that the letter would be inserted endwise into this compartment instead of lengthwise. A comparison of the Figures 2 and 6, however, will reveal the similarity of the sealed envelopes, both as to shape and arrangement of the printed and written matter thereon and the location of the postage.

The advantage of an envelope constructed in the manner described resides primarily in the simple and efficient manner of preparing the blanks. It is to be observed that the entire envelope is formed from a single blank, requiring only the application of the adhesive at the proper place to produce a finished envelope after the folding operation. An envelope of this character can be manufactured entirely by machines, thus eliminating expensive hand labor. Furthermore, the finished envelope permits strict compliance with the requirements of the Post Office Department without sacrificing adaptability of the envelope to the many uses for which it is designed.

It is obvious that certain departures and modifications may be resorted to, such as the disposition and relation of the several flaps, and for this reason it is to be observed

that the invention is not limited to the specific forms herein disclosed, except as they are described in the appended claims.

We claim as our invention:

5. 1. A duplex envelope comprising front, rear and inside panels connected by score lines, and foldable therealong with said inside panel interposed between said front and rear panels, said inside panel being sealed 10 along two of its free edges to said front panel thereby forming a separate compartment of reduced size opening along a portion of one edge of the envelope and separate sealing flaps along said last mentioned edge, 15 one for the opening to said compartment and another for permanently sealing the remaining portion of said edge.
2. A duplex envelope comprising front and rear panels of equal size and an inside panel of reduced width, said panels being foldable along parallel score lines with said inside panel between said front and rear panels, said inside panel being sealed to said front panel along the edge thereof parallel 25 with the line of folding thereof, and along one edge transverse thereto, thereby forming a compartment of reduced size having an opening along one edge of the envelope and flaps along the corresponding edge of said front panel, and one for sealing the opening to said compartment, and the other for permanently sealing the portion of the edge adjacent said compartment.
3. A duplex envelope formed from a blank 30 cut from a single sheet of paper, and comprising front, rear, and inside panels, foldable in super-imposed relation along parallel fold lines with said inside panel between

said front and rear panels, the free edge parallel with said fold lines, and one end 40 portion of said inside panel being sealed to said front panel, flaps for closing the openings formed by the free edges of said front and rear panels transverse to said fold lines, and flaps along the free edge of said front 45 panel parallel with the fold lines, one of said flaps being permanently sealed over the edge adjacent said sealed end portion of the inside panel, and the other forming a sealing flap for a compartment of reduced dimension 50 formed between said inside and front panels.

4. A duplex envelope formed from a blank cut from a single sheet of paper, and comprising front, rear, and inside panels, said panels being foldable in superimposed relation along parallel fold lines with said inside panel between said front and rear panels, and the free edge parallel with said fold lines, and one end portion of said inside panel being sealed to said front panel, flaps 60 55 6 and 12 for closing the openings formed along opposite edges of said front and rear panels, and flaps along the free edge of said front panel parallel with the fold lines, one of said flaps being permanently sealed over 65 the rear panel and throughout the sealed end portion of the inside panel, and the other forming a sealing flap for a compartment of reduced dimension formed between said inside and front panels.

In witness whereof, we hereunto subscribe our names this 31st day of January, A. D., 1921.

EMANUEL J. LEWIS.
JAMES G. McGREEVY.
